UNITED STATES PATENT OFFICE.

JAMES K. LOWE, OF DENISON, TEXAS.

BANK-DEPOSIT RECEIVER.

1,425,400.

Specification of Letters Patent. Patented Aug. 8, 1922.

Application filed November 1, 1921. Serial No. 512,004.

To all whom it may concern:

Be it known that I, JAMES K. LOWE, a citizen of the United States, residing at Denison, in the county of Grayson and 5 State of Texas, have invented certain new and useful Improvements in a Bank-Deposit Receiver; and I do hereby declare the following to be a full, clear, and exact description of the invention, such as will 10 enable others skilled in the art to which it appertains to make and use the same.

Banking institutions generally have fixed hours for receiving deposits and these hours are usually such as to conflict with hours of 15 toil so that the artizan, clerk and other wage earner cannot conveniently and without loss of time deposit savings. As a result many toilers do not lay aside savings which they otherwise would do if facilities were afforded.

The present invention provides a depository for the reception of savings, account books and the like, which is placed in a convenient position in a bank and safe guarded 25 and adapted to receive deposits outside of regular hours both early and late.

Other objects and advantages will be apparent and suggest themselves as the nature of the invention is understood.

30 While the drawing illustrates an embodiment of the invention it is to be understood that in adapting the same to meet different conditions and requirements, various changes in the form, proportion and minor details 35 of construction may be resorted to without departing from the nature of the invention.

Referring to the accompanying drawing forming a part of the specification,

40 Figure 1 is a perspective view of a depository constructed in accordance with and embodying the essential features of the invention.

Figure 2 is a sectional detail thereof, and Figure 3 is a further detail.

45 Corresponding and like parts are referred to in the following description and designated in the several views of the drawings by like reference characters.

In accordance with the present invention 50 a box-like structure 1 is provided and may be of any capacity and substantial construction. An opening 2 is provided in the front of the box 1 in the top thereof and is designed to receive the deposits. A door 3 is 55 adapted to close the opening 2 and is slidably mounted. A substantially horizontal

plate 4 is connected with the sliding door 3 so as to move therewith. When the door 3 is pushed aside to uncover the opening 2, the plate 4 occupies a position in line with 60 the opening 2 and is adapted to receive the deposits. A housing 5 in line with the bottom of the opening 2 and wholly to one side of said opening receives the plate 4 which is slidable therein. A slot 6 formed in the 65 front of the box 1 is in line with the housing 5 and receives the forward edge portion of the plate 4 which projects therethrough. The projecting edge of the plate 4 is bent to lie against the front of the box 1 and prevents possible displacement of the plate. The plate 4 is of such relative width that when the opening 2 is fully uncovered, the portion of the plate remains in the housing 5 to admit of the latter forming a substantial 70 support therefor. A hood 7 extends along the side and over the top of the opening 2 whereby to prevent displacement of the deposit and retain the same upon the plate 4. After a deposit has been made the 75 opening 2 is closed by sliding the door 3 and plate 4 laterally. During this movement the deposit resting upon the plate 4 is pushed therefrom by the wall of the hood 7 adjacent the housing 5 when the plate 4 80 is withdrawn from beneath the deposit and fails to further support the same the deposit drops and is received in the lower portion of the box 1 and is adapted to be removed 85 therefrom by means of a door 8 which is securely locked, the key being in the possession of the receiving teller of the bank or other person authorized to make the collection.

A chute 9 within the box 1 has its upper 90 receiving end in line with the bottom of the opening 2 so that when the deposit drops from the plate 4 in the closing of the opening 2 it enters the chute 9 and is directed thereby to the lower portion of the box 95 designed to receive the deposit. The chute 9 is curved or deflected in its length to prevent unauthorized removal of the contents of the box therethrough. The chute 9 may be of any construction and relative arrangement so long as it serves the purpose stated.

During regular banking hours the depository may be set aside so as not to be in the way and outside of banking hours both early and late the depository may be placed in 110 any convenient position and safeguarded so that depositors may be protected as to their

deposits and enabled to make the same conveniently and without loss of time and with the assurance of receiving proper credit therefor.

5 While the invention is particularly adapted for banks, it is to be understood that it is susceptible of use in connection with business of every description including stores, shops and pursuits of every nature whereby 10 to encourage and promote savings.

Having thus described the invention, what I claim is:—

15 1. A depositary comprising a box having an opening for receiving the deposits, a sliding door for closing the receiving opening and a plate movable with the sliding door and adapted to be brought opposite the receiving opening when the same has been uncovered by the sliding of the door to one 20 side.

20 2. A depositary comprising a box having a receiving opening for the deposits, a sliding door for closing the receiving opening, a plate movable with the sliding door and 25 adapted to occupy a position opposite the receiving opening when the same is uncovered, and a housing for said plate and adapted to form a support therefor and for the sliding door.

30 3. A depositary comprising a box having a receiving opening for the deposits, a sliding door for closing the receiving opening, a plate movable with the sliding door and adapted to occupy a position opposite the

receiving opening when the same is uncovered, a housing for said plate and adapted to form a support therefor and for the sliding door, and a hood extending along the side and over the top of the receiving opening, the wall adjacent the housing serving 40 to displace the deposits from the plate when closing the receiving opening. 35

4. A depositary comprising a box having a receiving opening in its upper portion, a closure for the receiving opening, a plate 45 movable with the closure and adapted to receive the deposits, means for displacing the deposits from the plate and a chute for receiving the deposits and directing them into the lower portion of the box. 50

5. A depositary comprising a box having a receiving opening in its upper portion, a sliding door closing the receiving opening, a plate movable with the door and adapted to receive the deposits, a housing for the plate, a 55 hood extending along the sides and over the top of the receiving opening and a chute having its receiving end in line with the receiving opening, said chute being deflected in its length and adapted to deliver the deposits in the lower portion of the box. 60

In testimony whereof I affix my signature in presence of two witnesses.

JAMES K. LOWE.
